UNITED STATES PATENT OFFICE

149,456

DESIGN FOR A FINGER RING

Theodore F. Strub, Chicago, Ill.

Application March 27, 1947, Serial No. 137,951

Term of patent 14 years

(CL. D45—10)

To all whom it may concern:

Be it known that I, Theodore F. Strub, a citizen of the United States, residing at Chicago, in the county of Cook and State of Illinois, have invented a new, original, and ornamental Design for Finger Rings, of which the following is a specification, reference being had to the accompanying drawing, forming part thereof.

In the drawing:

Fig. 1 is a view in front elevation of a finger ring, showing my new design.

Fig. 2 is a side view of the finger ring shown in Fig. 1.

Fig. 3 is a top plan view of the finger ring shown in Fig. 1, and

Fig. 4 is a rear view of the finger ring shown in Fig. 1.

I claim:

The ornamental design for a finger ring, as shown.

THEODORE F. STRUB.
